UNITED STATES PATENT OFFICE.

CARL R. WALLER, OF TRENTON, NEW JERSEY, ASSIGNOR TO DE LAVAL STEAM TURBINE COMPANY, OF TRENTON, NEW JERSEY, A CORPORATION OF NEW JERSEY.

CONTROL FOR STEAM TURBINES.

Application filed July 31, 1922. Serial No. 578,573.

This invention relates to control devices for steam turbines and more particularly relates to means for varying the effective nozzle area of one or more of the diaphragms.

In steam turbines of the bleeder type from which a large amount of steam is bled from a point intermediate the inlet and outlet of the turbine, it is necessary in order to obtain 10 the highest efficiency to vary the nozzle area in at least some of the diaphragms.

The object of my invention is to provide a simple and efficient means for varying the effective nozzle area of one or more of the 15 diaphragms to substantially maintain a predetermined pressure in one or more of the chambers or the bleed passage.

The precise nature of my invention will be best understood by reference to the accompanying drawings, it being premised, however, that changes may be made in the details of construction without departing from the spirit and scope of my invention as defined in the appended claims.

25 Fig. 1 is a sectional view of a portion of a steam turbine with one form of my control device shown in connection therewith.

Fig. 2 is a similar sectional view at right angles to Fig. 1.

30 Fig. 3 is a detail sectional view through one of the control valves.

Fig. 4 is a detail sectional view of a master valve on a larger scale than that shown in Fig. 2.

35 Fig. 5 is a detail sectional view on the line 5—5 of Fig. 4.

Fig. 6 is a face view of the handle for actuating a master valve.

In these drawings, the reference character 40 6, 6 designates a two-part casing of the turbine, and 7 is a shaft rotatably mounted therein. 8^a, 8^b and 8^c are three turbine wheels, which, together with six other such wheels, are secured to the shaft 7.

45 The casing 6 is provided with dividing walls 9 and 10. 11 is a chamber in front of wall 9 in which is located the first turbine wheel and a diaphragm therefor, and which wheel is also secured to shaft 7. 12^a, 12^b and 12^c are diaphragms in front of the wheels 8^a, 8^b and 8^c, respectively. The diaphragm 12^a is mounted in wall 9, while diaphragms 12^b, 12^c, as well as six other diaphragms, similar to diaphragm 12^c, are

55 mounted in the wall or partition 10. Each diaphragm is located in front of its wheel and is provided with nozzles for directing the steam to the vanes of its wheel. 13^a and 13^b are shaft-packing rings between the different stages and within their respective 60 diaphragms 12^a and 12^b. 14 is a chamber between walls 9 and 10 and diaphragms 12^a and 12^b, and is provided with a bleed outlet 14^a, through which steam is bled.

65 Diaphragm 12^c and those beyond said diaphragm are provided with the usual nozzles 16 for directing the steam to the vanes of their wheels. Diaphragms 12^a and 12^b, however, are each provided with several sets 70 of nozzles.

75 Diaphragm 12^b is provided with seven sets of nozzles 17^a, 17^b, 17^c, 17^d, 17^e, 17^f and 17^g. Nozzles 17^a communicate directly with chamber 14, while the other sets of nozzles communicate with nozzle chambers 18^b, 18^c, 18^d, 18^e and 18^g, respectively in the diaphragm 12^b.

80 Steam is admitted to each of chambers 18^b to 18^g from chamber 14, through a port which is opened and closed by a control valve, such as shown in Fig. 3. Nozzle chambers 18^b to 18^e are merely provided with a single valve-controlled port, while chamber 18^g is controlled by means of two such 85 ports and valves, as clearly shown in Fig. 2.

85 In Fig. 3 I have shown, for example, a section through the valve and its actuating mechanism for controlling the admission of fluid to chamber 18^b in diaphragm 12^b, which I will now describe.

90 Threaded in an opening in the diaphragm 12^b is a port member 19 having a central boss 20 connected thereto by means of integral spider arms.

95 Connected to this boss 20 by means of a threaded extension 21 is a support having an externally threaded head 22.

100 23 is a circular collapsible diaphragm connected at one end to head 22 by a flanged ring 24, while the other end of said diaphragm is secured to a valve 25 by a nut 26. Surrounding the extension 21 and interposed between the head 22 and valve 25 is a spring 27, which tends to retain the valve on its seat on port member 19 and prevent the admission of steam to chamber 18^b when the valve is seated.

105 The ends of the collapsible diaphragm are

connected to head member 22 and valve 25 so as to form steam-tight joints and to form a pressure chamber 28 within the collapsible diaphragm, which is in communication at 5 one end with chamber 18^b through the opening in the valve 25 through which the extension 21 extends. The other end of this diaphragm chamber 28 is in communication with a master valve mechanism 29 through 10 a pipe 30, see Fig. 2.

When all the valves 25 carried by diaphragm 12^a are closed, the only nozzles which direct steam to the vanes of wheel 8^b are nozzles of the set 17^a, which are always 15 open.

When it is desired to open any of the valves 25 to admit steam to any or all of chambers 18^b to 18^e, pressure is exhausted from the chambers 28 through pipes 30, as 20 hereinafter described, and as the outlet through pipes 30 is considerably greater than the area of opening through the valves, the pressure on the under sides of the valves will raise them from their seats against the 25 action of their springs 27 and permit a free flow of steam from chamber 14 through the opened ports into the nozzle chambers 18^b to 18^e.

The diaphragm 12^a is provided with similar sets of nozzles and nozzle chambers provided with control valves 31, which valves are in turn controlled from a master valve 32, which is identical with valve 29.

The master valve shown in Figs. 4 to 6 35 comprises a casing 33, which is secured to casing 6. 34 is a head closing one end of a chamber 35, and in which chamber is rotatably mounted a valve member 36. The valve 36 is connected to a valve stem 37, 40 which passes through a stuffing box 38 in the head 34. 39 is a valve-operating handle on the outer end of stem 37, the hub of which is rotatably mounted in a bearing-supporting member 40, supported by extensions from the head 34. 40^a is a spring-pressed locking lever on handle 39 having a projection arranged to be seated in any one of seven detents 41 in the body of the bearing 40 for the handle, whereby the valve 45 36 may be locked in any one of seven positions for the purpose hereinafter described.

The handle 39 is also provided with a pointer 42 which is arranged to move over a graduated plate 43 on the bearing 40, and 55 on which plate are numerals 1 to 6. The various members are so arranged that when the pointer 42 points to a numeral on plate 43, the numeral indicates the number of control valves that are open.

60 The valve casing 33 is provided with six ports 44^b, 44^c, 44^d, 44^e, 44^f and 44^g, which communicate with chamber 35 in the valve casing and are also each connected, by a pipe 30, with pressure chambers 28 communicating with chamber 18^b to 18^e, respec-

tively, in the diaphragm 12^b. 45 is a pipe connecting the chamber 35 in the valve casing 33 with a low pressure chamber of the turbine, which in this case is chamber 15. 46 is a similar pipe connecting the chamber of master valve 32 with pipe 45. The valve 36 is provided with a cut-away portion as shown in Fig. 5, whereby the ports 44^b to 44^g are successively placed in communication with chamber 35, or cut off 75 therefrom, in reverse order.

In the drawings as the parts are set by master valve 39, chambers 18^b, 18^c and 18^d are open to steam from chamber 14, while the valves of chambers 18^e, 18^f and 18^g are 80 closed so that steam is delivered to wheel 8^b through nozzles 17^a to 17^d, but not through nozzles 17^e, 17^f and 17^g.

If handle 39 is shifted counter-clockwise one notch to bring pointer 42 opposite the 85 numeral 2 on plate 43, valve 36 will be shifted to cover port 44^a. This covering of port 44^a will permit pressure to build up in chamber 28 which is in communication with chamber 18^d above valve 25 controlling the port leading to chamber 18^d, and as soon as the pressure therein, plus the pressure of spring 27 therein, exceeds the steam pressure on the bottom of the said valve, said valve will close and cut off the 90 supply of steam to chamber 18^d. If handle 39 is moved clockwise one point from that shown in Fig. 6, valve 36 will also be shifted clockwise one point from that shown in Fig. 5 and open port 44^e to exhaust through pipe 95 45 with the low pressure chamber 15. This opening of port 44^e to exhaust will exhaust the pressure in diaphragm chamber 28 above control valve 25 for the port of nozzle chamber 18^e, and as soon as the pressure therein, plus the spring pressure, is reduced below the steam pressure on the under side of the said valve 25, said valve will be opened by the steam pressure and steam will now be admitted to nozzle chambers 18^b, 18^c, 18^d and 100 18^g from chamber 14.

In the operation of the turbine shown, steam is admitted through the first diaphragm to the first wheel to chamber 11. From chamber 11 the steam passes through 115 the open nozzles in diaphragm 12^a, into chamber 14. Some of the steam is bled from chamber 14 through opening 14^a for the purpose for which it is to be used, while the remainder passes through the open nozzles 120 in diaphragm 12^b, and between the vanes of wheel 8^b, and then through the nozzles in the successive diaphragms and wheels to chamber 15, from which the steam passes to exhaust.

Assuming that the turbine is developing 125 80% load and that 10% of the steam is drawn through opening 14^a and at which time the pressure in chamber 11 is 100 lbs., and the pressure in chamber 14 is 60 lbs., 130

which would mean that steam is extracted from the turbine through opening 14^a at 60 lbs. pressure:

Should the demand for extracted steam increase, the pressure in chamber 14 would drop, and to restore the pressure in said chamber, one or more of valves 25 controlling the ports to the nozzle chambers in diaphragm 12^b are closed to reduce the nozzle area of diaphragm 12^b.

It will also be understood that the pressure in chamber 11 may also be controlled by the control valves in diaphragm 12^a, through the medium of the master valve 32.

The advantages of my invention result from the provision of means for varying the nozzle area of one or more of the diaphragms of a steam turbine from a single point of control, whereby the nozzle area may readily be increased or decreased in stages from the minimum area to the maximum area to control the pressure in a predetermined stage or chamber of the turbine, and thereby deliver steam to a point of use at a substantially uniform pressure between the pressures of the steam at the inlet and outlet ends of the turbine.

Another advantage results from the provision of a control valve arrangement for the nozzles, together with a master valve, whereby the control valves are actuated by steam pressure controlled by the master valve.

A still further advantage results from the provision of control valves which are actuated by the steam passing through the turbine, whereby I am enabled to dispense with mechanically actuated mechanism, which enables me to provide simple, effective, readily operated controlling means for actuating the control valves, and which controlling means can be operated with a minimum amount of effort by the engineer.

Having now fully described my invention, what I claim and desire to protect by Letters Patent is:

1. A separating diaphragm for insertion in a turbine casing for separating a pressure chamber in the casing from another pressure chamber in the casing, having a plurality of nozzle chambers therein provided with nozzles opening through one side of the diaphragm, each chamber having a port opening through the other side of the diaphragm, and fluid pressure actuated means for each valve connected thereto and supported on the diaphragm and arranged to be located within a pressure chamber in the turbine casing.

2. A steam turbine having a casing, diaphragms therein dividing the casing into high pressure, low pressure and intermediate pressure chambers, there being a steam bleed leading from the intermediate pressure chamber, a rotor having a blade in each

pressure chamber, there being a plurality of nozzle chambers in one of the diaphragms, each having nozzles opening into the adjacent chamber of lower pressure, there being a port communicating with each nozzle chamber and the adjacent higher pressure chamber, a valve for controlling each port mounted on the diaphragm a separate steam pressure actuated valve-actuating mechanism for each valve mounted on the diaphragm within a pressure chamber, a master valve, steam connections between the master valve and each of the valve actuating mechanisms, and means for actuating the master valve for controlling the opening and closing of the valves for the ports.

3. A steam turbine having a casing, diaphragms therein dividing the casing into high pressure, low pressure and intermediate pressure chambers, there being a steam bleed leading from the intermediate pressure chamber, a rotor having a blade in each pressure chamber, there being a plurality of nozzle chambers in each of the diaphragms, each having nozzles opening into the adjacent chamber of lower pressure, there being a port communicating with each nozzle chamber and the adjacent higher pressure chamber, a valve for controlling each port mounted on its diaphragm, a separate steam pressure actuated valve-actuating mechanism for each valve mounted on its diaphragm, two master valves, steam connections between one master valve and each of the valve actuating mechanisms on one diaphragm, similar connections between the second master valve and the valve actuating mechanisms on the other diaphragm, and means for actuating each of the master valves for closing and opening the ports.

4. A steam turbine having a casing, diaphragms therein dividing the casing into high pressure, low pressure and intermediate pressure chambers, there being a steam bleed leading from the intermediate pressure chamber, a rotor having a blade in each pressure chamber, there being a plurality of nozzle chambers in one of the diaphragms, each having nozzles opening into the adjacent chamber of lower pressure, there being a port communicating with each nozzle chamber and the adjacent higher pressure chamber, a valve for controlling each port mounted on the diaphragm, a separate steam pressure actuated valve-actuating mechanism for each valve mounted on the diaphragm and within a pressure chamber, a master valve within the casing, steam connections between the master valve and each of the valve actuating mechanisms, and a valve stem extending from the master valve outwardly through the valve casing.

5. A separating diaphragm for insertion in a turbine casing for separating a pressure chamber in the casing from another pressure

chamber in the casing, having a plurality of nozzle chambers therein provided with nozzles opening through one side of the diaphragm, a valve for each port carried by the diaphragm, a collapsible diaphragm connected to each valve and supported by the separating diaphragm, a spring for moving each valve to its closed position within its collapsible diaphragm, there being a pressure chamber formed by each collapsible dia-

phragm, and a fluid pressure pipe extending from each of the diaphragm chambers arranged to be connected to a master valve for controlling the pressure in the diaphragm chambers for opening and closing the valves. 15

In testimony of which invention, I have hereunto set my hand, at Trenton N. J., on this 28th day of July, 1922.

CARL R. WALLER.
